UNITED STATES PATENT OFFICE.

WALTER E. COFFIN, OF CLEVELAND, OHIO, ASSIGNOR TO THE NATIONAL MALLEABLE
CASTINGS COMPANY, OF CLEVELAND, OHIO, A CORPORATION OF OHIO.

RAILWAY-CAR TRUCK.

1,049,209.

Specification of Letters Patent.

Patented Dec. 31, 1912.

Application filed April 19, 1911. Serial No. 622,065.

To all whom it may concern:

Be it known that I, WALTER E. COFFIN, of Cleveland, Cuyahoga county, Ohio, have invented a new and useful Improvement in 5 Railway-Car Trucks, of which the following is a full, clear, and exact description, reference being had to the accompanying drawings, forming part of this specification, in which—

10 Figure 1 is a side view, partly in section, of a truck embodying my invention; Fig. 2 is a plan view of a portion of the truck, also partly in section; Fig. 3 is a partial section on the line III—III of Fig. 1; Fig. 4 is an inverted plan view showing the manner in which the tie bar is secured; Fig. 5 is a perspective view of one of the bolster wearing shoes; and Fig. 6 is a perspective view of 15 one of the side frame wearing shoes.

20 My invention has relation to railway car trucks, and is designed to provide means of novel, simple, and convenient character for permitting the ready removal and insertion of the bolster in the side frames; also to provide means of novel character for securing the spring plank to the truck side frames; and also to provide means of novel character for securing the tension members and tie bars of the side frames to the compression member.

25 The nature of my invention will be best understood by reference to the accompanying drawings, in which I have shown the preferred embodiment thereof, and which 30 will now be described, it being premised, however, that various changes may be made in the details of construction and arrangement of the several parts by those skilled in the art without departing from the spirit and scope of my invention as defined in the appended claims.

35 In these drawings, I have shown a truck having a side frame of that class composed of both wrought and cast members, the cast portion comprising the compression member 2 having the integral columns 3 connected at their lower ends by the portion 4, which is rounded at its under side to form a curved bearing for the wrought tension member 5, and which, at its upper side, forms a seat 6 for the springs 7 which support the bolster 8. The lower side of the portion 4 is rounded to a long radius; and the central portion 40 of the tension member which fits this rounded portion has substantially the form of a

catenary curve, the end portions of the tension member extending in substantially straight lines from the terminations of this curve to a point adjacent to the upper inner sides of the journal boxes, where they are bent horizontally outward and underneath the end portions 2^a of the compression member, as shown in Fig. 1, and are connected thereto by journal box bolts 9, or any other suitable means. This form of the tension member, however, is not my invention, but is the invention of Chester K. Brooks, of Cleveland, Ohio. The side frame window, which is bounded at its top by the compression member 2 and at the sides by the columns 3, and at the bottom by the seat 6, is widened at its upper portion sufficiently to permit of the insertion at each side of the side frame wearing shoes 10. These shoes are of sufficient thickness so that when seated in the widened portion of the window, their inner faces will be flush with the inner faces of the side walls of the narrower portion of the window. The bolster 8 may be of any well known or suitable form, and 45 is provided near each end with side guides 11, to seat the bolster wearing shoes 12, which are riveted or otherwise rigidly attached to the bolster.

50 In assembling the truck, the bolster with its attached wearing shoes, is inserted laterally through the upper widened window portion of the cast member of the side frame, and having been so inserted to such a point that the flanges 12^a of said shoes come into 55 register with the lower portions of the columns 3 at the narrower part of the window, the bolster can be dropped down sufficiently within the window to permit the side frame wearing shoes 10 to be inserted in their 60 seats. After these shoes 10 have been inserted in position, the bolster is again raised and the springs 7 placed beneath it. The entire structure is then so interlocked that the shoes 10 cannot be withdrawn. The side 65 flanges 12^a of the shoes 12 fit partially over the side edges of the shoes 10, and the side flanges 10^a of the shoes 10 embrace the sides of the columns, as clearly seen in Fig. 2.

70 The portion 4 of the cast member has cast 75 integral therewith the depending wing or key portion 4^a, which enters a slot 13 in the wrought tension member 5, and also a similar slot in the tie bar 14. In order to avoid weakening of the tension member 5 and tie 80 110

bar 14 by cutting the slots for the wing or key portion 13 out of the solid metal, these slots are preferably formed by inserting a spreading tool or die which does not cut out the metal of this point but simply spreads it apart, leaving the same amount of metal in cross section through the split portion as at the other points of these members. The wing or key member 4^a is formed with transverse holes for the insertion of the key bolts 15, which may be secured by cotter pins 16, or by other suitable means, and whereby the cast compression member of the side frame, the tension member, and the tie bar, are all interlocked and are prevented from becoming disengaged.

The seats 6 of the compression member are each formed with a vertically extending slot or recess 17 (see Fig. 3), adapted to receive 20 the downwardly bent end 18 of the spring plank 19. This spring plank 19 is preferably of pressed steel, dished out at its middle portion, as shown at 20, with its end portions 18 bent downwardly at substantially 25 right angles to engage the recesses 17. So much of the floor of the seats 6 as receive the end portions of the spring plank are lower than the remaining portions of said seat by an amount equal to the thickness of 30 the spring plank, so that when the latter is placed in position, its upper surface will lie flush with the general surface of said seat, thereby providing a flat bearing of the same height for the entire group of bolster 35 springs. After the springs have been placed in position, the spring plank is prevented by the springs from becoming disengaged from the side frames, and thereby forms a rigid cross-connection between the two side frames, 40 which cannot become disengaged therefrom as long as the springs remain in place.

It will be understood that some of the features of my invention are not limited to the particular form of truck side frame or bolster which I have herein shown and de-

scribed, but are applicable to truck side frames and bolsters of various types.

What I claim is:—

1. A truck side frame provided with a window widened at its upper portion, wearing shoes seated in the widened portion of the window, and a bolster having wearing shoes secured to opposite sides thereof and adapted to bear against and engage the first named wearing shoes; substantially as described. 55

2. A truck side frame having a window therein widened at its upper portion, flanged wearing shoes seated at opposite sides of the widened portion of the window, a bolster 60 having lateral guides at its ends, and flanged wearing shoes fixedly secured in said recesses and engaging the first named wearing shoes; substantially as described.

3. A car truck having a compression member and a slotted tension member, the compression member having column guides provided with a connecting portion at the bottom of the bolster opening, a rib depending from the connecting portion adapted for securing in a slot in the tension member, the metal of the tension member being of uniform cross-sectional area between its points of support. 65

4. In a car truck side frame, a compression member, a slotted tension member, bolster guides formed with a connecting portion which serves as a bearing for the tension member, the said connecting portion having a depending rib adapted to be secured in a slot in the tension member, the metal of said tension member being of substantially uniform cross sectional area between its points of support. 70

In testimony whereof, I have hereunto set my hand.

WALTER E. COFFIN.
